DESIGN FOR A MULTIPOSITION FOOTSTOOL OR LIKE ARTICLE

Richard C. Crego, Cleveland Heights, Ohio

Application April 16, 1934, Serial No. 51,422

Term of patent 3½ years

To all whom it may concern:

Be it known that I, RICHARD C. CREGO, a citizen of the United States, residing at Cleveland Heights, in the county of Cuyahoga, and State of Ohio, have invented a new, original, and ornamental Design for a Multi-Position Footstool or Like Article, of which the following is a specification; reference being had to the accompanying drawing, forming a part hereof:

In the accompanying drawing:

Figure 1 is an end elevational view of a footstool showing my new design;

Figure 2 is a side elevation view thereof and; Figure 3 is a perspective view of the same footstool.

I claim:

The ornamental design for a multi-position footstool or like article substantially as shown.

In testimony whereof, I hereunto affix my signature this 5th day of April, 1934.

RICHARD C. CREGO.
